United States Patent

Des. 240,259
Patented June 8, 1976

240,259

LIGHTING FIXTURE

Robert E. Walker, Bellevue, and G. Thomas Henderson,
Bainbridge Island, Wash., assignors to Cascade Pacific
Lumber Co., Inc.

Filed July 17, 1974, Ser. No. 489,375

Term of patent 14 years

Int. Cl. D26—03

U.S. Cl. D48—31

FIG. 1

FIG. 2

FIG. 3

FIG. 1 is a perspective view of a lighting fixture incorporating our new design;

FIG. 2 is a top plan view thereof; and

FIG. 3 is a front elevation view thereof.

The sides of the device which are not shown are substantially identical to sides disclosed in FIG. 3. The bottom of the device is substantially plain and unornamented.

We claim:

The ornamental design for a lighting fixture, substantially as shown and described.
